UNITED STATES PATENT OFFICE.

CHARLES BAGHURST, OF ADELAIDE, SOUTH AUSTRALIA, AUSTRALIA, AND EDMUND P. KINNE, OF ALLIANCE, OHIO, ASSIGNORS TO AMERICAN STEEL FOUNDRIES, OF CHICAGO, ILLINOIS, A CORPORATION OF NEW JERSEY.

CAR COUPLER.

Application filed April 30, 1925. Serial No. 26,852.

This invention relates to a railway car coupler, particularly for use with foreign types of car couplers during the transitional period.

5 It is common practice in foreign countries to couple railway cars by means of a chain and hook. Near each side of the car at the ends thereof are provided buffers or resilient plungers. In some foreign countries steps 10 are being taken toward the adoption of a standard coupler such as is used in the United States, but inasmuch as the transition from one type to the other cannot be made all at once, means must be provided 15 to couple cars equipped with old and new apparatus.

One object of the present invention is to provide a car coupler of the M. C. B. type, with simple and efficient means whereby it 20 may be easily and safely connected and disconnected with respect to a foreign type of coupler.

Another object is to provide a M. C. B. type of coupler with a chain-engaging pulling 25 lug having means for locking the chain against accidental disengagement.

These and other objects are accomplished by means of the arrangement shown on the accompanying sheet of drawings, in which— 30 Fig. 1 is a top plan view of a car coupler of the M. C. B. type provided with chain attachment means whereby the chain is connected and locked to the pulling lug against accidental disengagement;

35 Fig. 2 is a side elevation of the same coupler, and

Fig. 3 is a detail elevational view showing the pulling lug having connected thereto a chain link which is shown in section.

40 The various novel features of the invention will be apparent from the following description and drawings and will be particularly pointed out in the appended claims.

Referring to the figures of the drawings, 45 it will be noted that the invention is illustrated in connection with a car coupler of the M. C. B. type, including a coupler head 10 and a knuckle 11 pivotally connected thereto by a pin 12, said coupler having 50 a shank 13.

As mentioned above, this coupler is to be used during the transitional period with a foreign type of car coupler in which there is used the usual chain and hook connection.

Two links 14 and 15 of such chain are shown 55 in dot and dash lines, the link 15 cooperating with a pulling lug 16 cast integrally on top of the coupler head 10. The main body portion of the pulling lug 16 is of a dimension which occupies substantially the entire 60 space between the arms of the link 15, and said pulling lug 16 is provided with a relatively large forwardly-spreading base 17, as best shown in Fig. 2. Rearwardly of the pulling lug 16 is a projection 18 which extends upwardly from the top of the coupler head 10 and which cooperates with the pulling lug in maintaining the link 15 in its proper operative position. More particularly, the projection 18 cooperates with what 70 may be termed a cap, lateral projections or a flange 19 formed integrally with the top of the pulling lug 16.

Referring more particularly to Figs. 1 and 3, it will be noted that the cap 19 is 75 of such lateral width as to prevent the disengagement of the link 15 when the link is in its normal position with its major axis lengthwise of the coupler shank. However, the cap 19 is sufficiently shallow in depth 80 forwardly and rearwardly to permit the application and withdrawal of the link with respect thereto when said link 15 has its major axis extending at right angles to the length of the coupler shank 13. The rear 85 of the cap 19 and the top of the projection 18 are spaced an amount which will just permit the free passage of the link through the opening between said cap 19 and projection 18. Said projection 18 additionally 90 functions to prevent a rearward movement of the link 15 in a manner to prevent its accidental disengagement from the pulling lug.

As shown in the figures, the link 15 is in 95 its operative position with respect to the pulling lug 16, in which position it will be noted that the link is locked against vertical displacement and locked against rearward displacement, and, as a matter of fact, 100 locked against any accidental displacement with respect to the pulling lug 16. The only way that said link 15 may be disengaged from said pulling lug is by sliding said link around the pulling lug until its major axis 105 is at right angles with respect to the length of the coupler shank 13, whereupon the link 15 may be raised vertically to be freed from

the pulling lug 16 and its locking cap 19. Of course, the position of the link under normal operating conditions would prevent such a disengaging movement accidentally.

5 We claim:

1. A car coupler of the M. C. B. type provided with a pulling lug on the top thereof, to be engaged by a link of a chain of a foreign type of coupler, said lug having a cap 10 extending transversely of the coupler for locking said link against accidental displacement.
2. A car coupler of the M. C. B. type provided with a pulling lug on the top thereof to be engaged by a link of a chain of a foreign type of coupler, said lug having a cap 15 extending from a plurality of sides of said lug and which will permit the application and withdrawal of a chain link when the latter is in a given position and which will prevent withdrawal of said link when 20 the latter is in a different position with respect to said lug.
3. A car coupler of the M. C. B. type provided with a pulling lug to be engaged by a link of a chain of a foreign type of coupler, said lug having a cap 25 extending crosswise of the coupler and which will permit the application and withdrawal of the 30 chain link when the latter has its major

axis extending at right angles to the length of the coupler shank and which will prevent the application and withdrawal of said link with respect to said lug when said link has its major axis extending in the same direction as the length of the coupler shank. 35

4. A car coupler of the M. C. B. type provided with a pulling lug to be engaged by a link of a chain of a foreign type of coupler, said lug having a cap for locking 40 said link against accidental displacement with respect thereto, and a projection on said coupler cooperating with said lug to form a receiving recess for the chain link.

5. A car coupler of the M. C. B. type provided with a pulling lug to be engaged by a link of a chain of a foreign type of coupler, said lug at one of its extremities having laterally-extending portions which act to prevent accidental displacement of 45 said link with respect to said pulling lug, and a projection on said coupler cooperating with said lug for forming a recess for the reception of said link. 50
